UNITED STATES PATENT OFFICE

168,162

COMBINED LAMP AND TRAY

Bill Laque, Menominee, Mich.

Application June 19, 1952, Serial No. 20,266

Term of patent 14 years

(Cl. D48—4)

To all whom it may concern:

Be it known that I, Bill Laque, a citizen of the United States, residing at Menominee, in the county of Menominee and State of Michigan, have invented a new, original, and ornamental Design for a Combined Lamp and Tray, of which the following is a specification, reference being had to the accompanying drawing, forming part thereof.

Figure 1 is a perspective view of a combined lamp and tray showing my new design;

Figure 2 is a front elevational view thereof; and

Figure 3 is a side elevational view of the same.

I claim:

The ornamental design for a combined lamp and tray, as shown.

BILL LAQUE.
